UNITED STATES PATENT OFFICE.

FRED L. FRIET AND JOSEPH FRIET, OF PARKERS PRAIRIE, MINNESOTA.

ALUMINUM BOAT.

Application filed October 14, 1926. Serial No. 141,601.

This invention relates to an aluminum boat structure and it consists in the novel features hereinafter described and claimed.

An object of the invention is to provide 5 in a boat structure of the character stated ribs of a special design and adapted particularly to be used in such a structure, seat braces of a special design and adaptation, corner braces, a bow piece, and an arrangement of gunwales all particularly designed to be used in a boat of the character stated.

A further object of the invention is to provide a general arrangement of the parts specified whereby the structure of the boat as an 15 entirety is rigidly braced and consequently is susceptible of withstanding the heavy strains to which it is subjected when being propelled through water. Also the boat structure is light in weight and may be readily transported over land or withdrawn or 20 launched in the water.

In the accompanying drawing:

Figure 1 is a top plan view of the aluminum boat.

25 Figure 2 is a transverse sectional view thereof cut on the line 2—2 of Figure 1.

Figure 3 is a perspective view of one of the seat braces of the boat structure.

As illustrated in the accompanying drawing the boat structure includes a hull 1, 30 preferably of aluminum, but which may be of any other suitable material as for instance, wood, metal or fiber board. Transversely disposed ribs 2 of aluminum are located interiorly of the hull 1 and are spaced from each other in parallel relation as shown in Figure 1 of the drawing. These ribs are connected at their ends with inner gunwale strips 3. Other gunwale strips 4 are 35 located interiorly of the hull 1 and are connected with the ribs 2 along lines spaced below the upper edge of the hull 1 and seat boards 5 rest at their ends upon the gunwale strips 4 and consequently are located below 40 the upper edges of the hull 1. Braces 6, of light metal as for instance, aluminum, are provided at their ends with transversely disposed heads 7 and the heads are provided with perforations 8 which are located be- 45 yond the side edges of the intermediate portions of the braces 6 as best shown in Figure 3 of the drawing. The heads 7 are disposed in planes at an angle to each other and the upper heads 7 are secured to the gunwale strips 3 and the lower heads 7 are secured 50 to the seat boards 5 by means of bolts, screws

or other securing devices whereby the intermediate portion of the braces 6 are disposed at angles with relation to the plane in which the seat boards 5 lie as best shown 60 in Figure 2 of the drawing.

Upper and lower gunwale strips 9 and 10 are applied to the exterior surface of the hull 1 and are spaced from each other in parallel relation. The strips 9 and 10 are 65 preferably of aluminum or other light metal. A bow piece 11 is inserted in the forward end of the hull and its upper surface is flush with the upper edges of the body of the hull 1. End brace pieces 12 are positioned in the stern corner of the hull of the boat and their upper surfaces are flush with the upper edges of the sides of the hull 1. 70

Hence, it will be seen that the seat boards 5 bear directly at their ends against the 75 upper portions of the ribs 2 and the seat boards 5 rest upon the lower inner gunwale strips 4. Also the braces 6 are upwardly and outwardly inclined from the median longitudinal dimension of the hull 80 of the boat and being connected at their ends with the seat boards 5 and the upper gunwale strips 3 serves to effectually hold the seat boards in proper position upon the gunwale strips 4 so that the upper edge 85 portions of the hull of the boat are effectually braced and the structure as an entirety may sustain the pressure of heavy strain against the exterior surface of the hull. The gunwale strips 9 and 10 serve to hold the 90 upper portions of the edges of the hull inwardly toward the ends of the seat boards and the braces 6 and consequently the sides of the hull cannot swerve in consequence of internal pressure or weight carried by the 95 hull. The ribs 2 being of light metal serve to hold the intermediate portion of the hull in proper shape so that the same cannot warp or twist in consequence of strain applied interiorly or exteriorly or in conse- 100 quence of strain due to the propulsion of the boat through the water by the use of an engine or other high power motor.

A floor structure is used in the boat and the said floor structure consists of a forward 105 section and a rear section. The forward floor section includes longitudinally disposed spaced floor strips 11 which are attached to cross pieces 12. As shown in the drawing seven strips are used but it is to 110 be understood that a greater or less number of strips may be employed if desired. Cleats

13 are mounted upon the intermediate strips 11 and may be used for holding oars (not shown) upon the floor of the boat or may be used as handles for lifting and carrying 5 the floor section. The rear floor section consists of spaced strips 14 which are mounted upon cross pieces 15 and as shown in the drawing five strips 14 are used; however, a greater or less number of strips may be 10 employed if desired. The floor is made in sections so that the sections may be readily removed from the bottom of the boat for cleaning and painting. The boat may be used for hunting or for any other desired 15 purpose.

From the foregoing description taken in conjunction with the accompanying drawing it will be seen that an aluminum boat of simple and durable structure is provided and 20 that the same has its parts and features so arranged and assembled as to render the structure strong and durable and capable of withstanding the excessive and heavy strain to which it is subjected when in use. 25 Furthermore, the boat is light in weight and may be easily and quickly transported from point to point and may be quickly launched in the water or withdrawn therefrom.

From the foregoing description of the construction of our improved device, it will be seen that we have provided a simple, inexpensive and efficient means for carrying out the objects of the invention.

While we have particularly described the 30 elements best adapted to perform the functions set forth, it is obvious that various changes in form, proportion and in the 35

minor details of construction may be resorted to without departing from the spirit or sacrificing any of the principles of the 40 invention.

Having thus described the invention, what is claimed is:

1. A boat structure comprising a hull, ribs disposed transversely thereof in spaced 45 relation, gunwale strips applied to the inner surfaces of the ribs and disposed longitudinally of the hull below the edges thereof, a seat board resting at its ends upon the gunwale strips and having end edges bearing against the inner surfaces of the ribs and outer gunwale strips applied to the exterior surface of the hull and disposed longitudinally thereof, and opposite the ends 50 of the seat board.

2. A boat structure comprising a hull, ribs disposed transversely thereof in spaced relation, upper and lower gunwale strips applied to the inner surfaces of the ribs and disposed longitudinally of the hull, a seat board resting at the ends upon the lower inner gunwale strips and having end edges bearing against the ribs, braces connected at their lower ends with the seat board and at their upper ends with the upper inner gunwale strips, outer gunwale strips applied to the exterior surface of the hull and disposed longitudinally thereof, and disposed 55 opposite the ends of the seat board.

In testimony whereof we affix our signatures.

FRED L. FRIET.
JOSEPH FRIET.
